JOINTED STRUCTURE

Mabel H. Gallagher, Chicago, Ill.

Application April 4, 1945, Serial No. 586,602

2 Claims. (Cl. 46—22)

1

This invention relates to a jointed structure, and more particularly to a separable structure of a plurality of parts each having integral joint-forming portions cooperating with corresponding portions on the other parts to hold the parts in assembled relation.

It is an object of this invention to provide a jointed structure of separable parts having interfitting portions for interlocking assembly thereof.

Another object is the provision of a simple joint for the assembly of separable parts of a jointed structure.

A further object of the invention is the provision of a structure having detachable parts which may be easily and quickly assembled and disassembled by means of a novel joint.

Another and further object is the provision of a simple and secure joint for detachably connecting separable members.

It is also an object of this invention to provide a novel joint for securing together and releasing the parts of a separable structure.

An additional object is the provision of a toy having separable parts formed with corresponding interfitting joint portions.

It is still another object of the invention to provide a separable structure provided with interlocking joint portions engageable and disengageable by relative movement between the parts substantially along a single line.

Other and further objects and advantages of the present invention will be apparent to those skilled in the art from the following description and appended drawings.

On the drawings:

Figure 1 is a side elevational view of a toy embodying my invention;

Figure 2 is an enlarged fragmentary plan view of the toy shown in Figure 1;

Figure 3 is a vertical sectional view taken along the line III—III of Figure 2.

In Figures 1 to 3, the invention is illustrated as applied to a toy horse, although it will be understood that the invention may equally well be applied to other toy figures, or to structural toys or the like, and that the invention is also applicable to jointed or separable structures other than toys.

The toy horse comprises a body portion 10, a separable head portion 11, and a separable tail portion 12. The body portion 10 is slotted at either end thereof. This slotted construction may be easily and conveniently provided by forming the body portion of a pair of identical outer

2

members 13 formed in the shape of the trunk and legs of a horse, and a central member 14 secured between the members 13 having its upper and lower surfaces flush with the corresponding surfaces of the members 13.

The member 14 is shorter than the trunk portion of the members 13, and as best shown in Figure 3, it has its forward end formed to provide an inclined surface 15 extending upwardly and rearwardly for a substantial portion of the length of the front end. Another inclined surface 16 offset rearwardly from the inclined portion 15 extends rearwardly and upwardly to the top of the member 14. The inclined surfaces 15 and 16 are in spaced overlapped relation, and are connected by a reversely curved surface to provide a projection 17 at the surface 15 and a recess 18 defined between the projection 17 and the surface 16, somewhat in the nature of an ogee curve. The surfaces 15 and 16 are shown at an angle of slightly less than 180 degrees relative to each other, although they may be otherwise disposed, as in parallel relation or at an angle greater than 180 degrees. The rear end of the central portion 14 is formed with inclined surfaces 15a and 16a, projection 17a, and recess 18a, corresponding to the surfaces 15 and 16, projection 17 and recess 18, respectively, of the front end of the member 14. The projection 17, however, is shown as rounded, while the projection 17a is shown as forming a relatively sharp angle or corner 19 with the inclined surface 15a.

The head part 11 has its rear or inner end formed with inclined surfaces 20 and 21 to abut against the surfaces 15 and 16, respectively, of the central part 14, and a recess 22 and a tongue 23 to interfit with the projection 17 and recess 18, respectively.

The tail part 12 has inclined surfaces 20a and 21a, recess 22a, and tongue 23a similar to the elements 20, 21, 22 and 23 of the head part 11, and formed to engage the surfaces 15a and 16a, projection 17a, and recess 18a, respectively, of the central part 14.

The head part 11 may be attached to the body part 10 by inserting the rear portion of the head part in the slot at the front end of the body part and engaging the tongue 23 in the recess 18, so that the corresponding inclined surfaces engage or abut each other and the projection 17 engages in the recess 22. Detachment of the parts is accomplished by a reverse operation. The tail part 12 may be attached and detached in the same manner as the head part 11.

The recesses 18 and 18a are of such depth that

a substantial sliding movement must occur between the inclined surfaces of the parts before the parts may be engaged or disengaged. The parts thus may be attached or detached only by movement in one direction or the other along substantially a single line. While the center of gravity of the head part 11, or of the tail part 12, is so disposed, the part 11 or 12 may be secured on the body part 10 simply by placing the tongue 23 or 23a at the upper portion of the inclined surface 16 or 16a and permitting the part to fall or slide by gravity into its attached position.

When the part 11 or 12 is in attached position any force applied to the part tending to move it downward, or to the front or rear, is resisted by the cooperating inclined surfaces and the interengaged projections and tongues. Even a force acting in a generally vertical direction will not serve to remove the part 11 or 12 unless it has a component acting along the line of movement previously referred to great enough to move the projections out of the recesses.

The parts 11 and 12 are illustrated as having the same width or thickness as the central part 14, but these parts may be of a different thickness, if desired, with only the portion thereof fitting within the slot in the body part 10 having substantially the same thickness as the central member 14.

The joint elements for the tail part 12, as shown in Figure 3, have dimensions different from those of the joint elements for securing the head part 11. This prevents the disposition of one part in the place where the other should be applied, since the dimensional differences will not permit interengagement by the joint elements of one of the detachable parts with the joint elements of the body part provided to coact with the joint elements of the other detachable part. Instead of providing the joint elements in different dimensions, or in addition to the dimensional differences, the joint for one part, as for the tail part 12, may have one or more of the elements formed in a different shape from the corresponding element or elements of the joint for the other part. Such difference in shape may, for example, be the provision of the sharp angle 19 on the projection 17a, but this example is illustrative only.

If desired, of course, the head and tail parts may each be provided with a slot, and the body part have portions to extend into the slots. In other words, the parts may be reversed in this respect.

Several head and tail parts of different shapes or sizes may be employed with a single body part 10, if desired, to permit assembly of the parts into toys of differing aspects. A child may assemble the toy without error because of the differences between the joint elements of the different parts. The assembled toy has the parts so locked together that the possibility of unintentional disassembly is very largely eliminated, by reason of the simple and efficient joint of this invention.

The invention is not limited in application to figure toys, since the joint is well adapted for use with construction or structural toys in which a plurality of blocks, bars, strips, and the like may be secured together in various combinations to simulate structures of various kinds. The invention may also be employed generally, being applicable to a wide variety of structures in which the parts are to be separably joined.

It will be obvious that the joint provided by this invention does not require that the inclined surfaces upon which a detachable member may be disclosed form the bottom of a slot, as shown in Figure 3. That is, it is not necessary to the invention that one of the members to be secured together provide a slot into which the other member may project. This is particularly true in the case of relatively wide or thick members, 5 which are not readily displaceable laterally relatively to each other. With relatively wide or thick members, a considerable lateral movement is necessary to cause separation, and requires that an entire member move laterally. A pivoting or 10 rotational movement of the member would result in binding between the members and thus prevent displacement thereof. Lateral movement, moreover, may be resisted by friction over a considerable area. Practically, therefore, in a great 15 many applications, the joint elements need not be disposed in a slot to prevent lateral displacement of the members.

It will, of course, be understood that various details of construction may be varied through a wide range without departing from the principles of this invention, and it is not the purpose to limit the patent granted hereon otherwise than necessitated by the scope of the appended claims.

I claim as my invention:

30 1. A toy comprising a solid body shaped in the similitude of an animal and having a separable head and a separable tail, said body having a slot at its head end and a second slot at its tail end, the sides of said slots being closed with the ends 35 of the slot being open, said head having a part enterable in the head end slot, said tail having a part enterable in the tail end slot, the head end slot and margins of the enterable parts of said head having complementary surfaces to interlock against relative rocking or tilting motion when the head is entered in its slot, the tail end slot and the margins of the enterable part of said tail having complementary surfaces to interlock against relative rocking or tilting motion when 40 said tail is entered in its slot, and the complementary surfaces of the head and the head end slot being different from the complementary surfaces of the tail and the tail end slot to prevent insertion of the tail into the head end slot and of the head into the tail end slot, said parts being 45 connectable and disconnectable by relative movement endwise of the slots with the direction of movement of the parts being connected and disconnected in planes parallel to the planes of the side surfaces of the body.

50 2. A toy comprising a solid body shaped in the similitude of an animal and having at least two separable members, said body having at least two slots in it to receive said members, the sides of 55 said slots being closed with the ends of the slot being open, each of said members having a part enterable in its slot, said slots and portions of 60 said enterable parts having complementary tongue and recess engagements to connect the parts and said body solely by sliding action and to interlock the parts and body against relative tilting movement, the complementary tongue and recess 65 engagements of a member and its slot being different from the complementary tongue and recess engagement of another member and its slot to prevent insertion of a member in any but its own slot, the parts being connectable and disconnectable by relative movement endwise of the 70 slots with the direction of movement of the parts being connected and disconnected in planes par-

allel to the planes of the side surfaces of the body.
